CLAIM

The ornamental designs for an exercise tire, as shown and described.

DESCRIPTION

FIG. 1 is an isometric view of the exercise tire of the present invention;

FIG. 2 is a side view of the exercise tire of FIG. 1, the other side view being a mirror image thereof;

FIG. 3 is a top view of the exercise tire of FIG. 1;

FIG. 4 is a bottom view of the exercise tire of FIG. 1;

FIG. 5 is an isometric view of another embodiment of the exercise tire of the present invention;

FIG. 6 is a side view of the exercise tire of FIG. 5, the other side view being a mirror image thereof;

FIG. 7 is a front view of the exercise tire of FIG. 5, the back view being a mirror image thereof;

FIG. 8 is a top view of the exercise tire of FIG. 5; and,

FIG. 9 is a bottom view of the exercise tire of FIG. 5.

The broken lines are for illustrative purposes only and form no part of the claimed design.

1 Claim, 9 Drawing Sheets
